SEAT FOR A CHILD'S HIGHCHAIR

Robert L. Hail and Alice L. Hail, Glendale, Mo.

Application July 12, 1954, Serial No. 31,386

Term of patent 14 years

(Cl. D15—1)

Fig. 1

Fig. 2

Fig. 3

Fig. 4

Fig. 1 is a perspective view of a seat for a child's highchair embodying our new design.

Figs. 2 and 3 are, respectively, a side elevation and a top plan view of the seat for a child's highchair illustrated in Fig. 1.

Fig. 4 is an inverted plan view of the seat for a child's highchair illustrated by Figs. 1, 2, and 3.

We claim:

The ornamental design for a seat for a child's highchair, as shown.
